UNITED STATES PATENT OFFICE

HENRY J. STEHLI, OF CEDAR GROVE, NEW JERSEY.

SINTERING MACHINE.

Application filed November 3, 1922. Serial No. 598,925.

To all whom it may concern:

Be it known that I, HENRY J. STEHLI, a citizen of the United States, and resident of Cedar Grove, in the county of Essex and 5 State of New Jersey, have invented certain new and useful Improvements in Sintering Machines, of which the following is a specification.

In certain kinds of machines for treating 10 ores, such as for desulphurizing and sintering ores, it has been customary to cause pallets or receptacles containing the ore to be treated to be moved over an air suction box or chest, whereby air is drawn into the box 15 through the ore on the pallets, the ore having been ignited by suitable means, so that combustion of the ore is maintained during its travel over the suction box. Various means have been provided to cause the pallets or ore receptacles to travel over the wind or suction box or boxes with a minimum loss of air drawn into the box other than through the material to be dried, roasted or sintered 20 in the pallets. The pallets or receptacles 25 have been arranged to slide along rails and have been provided with laterally disposed wheels that could rest upon tracks, but by reason of wear on the rubbing surfaces between the pallets and the rails, and due to 30 heat and dust conditions, no system of lubrication has been found to overcome the wear at such surfaces, so far as I know, whereby leakage of air into the wind or suction box occurs. Attempts have been made to 35 reduce the wear between the pallets and rails by supporting the weight of the pallets while over the wind or suction box by means of tracks under the wheels of the pallets, which has been only partially successful 40 because if the distance between the wind or suction box top and the bottoms of the pallets is left so as to be appreciable, serious leakage at once results, while on the other hand if such distance is very small wear 45 takes place in the wheels very shortly and allows the bottoms of the pallet to rest on the suction box top the same as if the wheels were not there. Attempts have been made to overcome such wear, as for instance by 50 extending the pallet sides down below the pallet bottom and making the seal against the side surfaces, and also by making deep grooves in the sides of the pallets and inserting a movable metal bar which rested 55 against the wind or suction box at the top and rode on it, thus making a seal until the

bar or the suction box surface wore. The efforts to make continuous tight joints between the moving pallets and the wind or suction box have proved unsatisfactory, because, due to the method of construction the wearing surfaces have been made of cast iron, malleable iron or steel, and the cost of replacement has been serious when the parts wore. 60

The object of my invention is to provide simple and effective means to produce practically air tight joints between the movable receptacles or pallets and the upper open portion of the wind or suction boxes which 70 will maintain a seal against the pallets by reason of the reduction of pressure within the boxes, the sealing means being flexible and relatively soft so as not to wear the metal of the receptacles or the wind boxes, and 75 whereby the sealing means may be readily removed and replaced at relatively low cost.

My invention comprises novel details of improvement and combinations of parts that will be more fully hereinafter set forth and 80 then pointed out in the claims.

Reference is to be had to the accompanying drawings forming a part hereof, wherein:

Fig. 1 is a side elevation of a machine for 85 treating ores embodying my invention;

Fig. 2 is a detail perspective view illustrating one form of sealing means between a pallet or receptacle and a wind or suction box; 90

Fig. 3 is an enlarged cross section of Fig. 1;

Figs. 4 and 5 are sectional details showing modified forms of sealing means between the receptacle or pallet and the wind box; 95

Fig. 6 is a sectional detail illustrating the lap of flexible sealing strips between the ends of adjacent pallets;

Fig. 7 is a cross section illustrating a dead plate and sealing means for the receptacles 100 of Fig. 3, and

Fig. 8 is a sectional detail illustrating the position of receptacle and sealing means of Fig. 5 with relation to the dead plate.

Similar numerals of reference indicate 105 corresponding parts.

The numeral 1 indicates the main frame of the machine, which may be of any suitable or usual construction. The receptacle or pallets for the ore or material to be treated 110 are indicated at 2, and may be of any suitable or usual construction, preferably pro-

vided with removable perforated grates 3 retained in place by means of pins or the like 4. The receptacles 2 are shown provided with grooved wheels 5 rotative upon hubs 6 or shafts 6 projecting from the sides of the receptacles, which grooved wheels are adapted to travel upon tracks supported by the frame 1. The upper tracks 7 are shown substantially horizontally disposed and spaced apart for the travel of the receptacles or pallets therebetween, which tracks may be supported on beams 8 carried by the main frame. Adjacent to the receptacle receiving ends of the tracks 7 means are provided to apply the receptacles to the tracks. I have illustrated sprocket wheels 9 which are carried by shaft 10 and which may be spaced apart to receive the wheels or rollers 5 of the receptacles or pallets to deliver the latter to the tracks 7. At their opposite ends the tracks 7 are shown curved downwardly and under at 7^a and outside of said curved parts 7^a is located the curved portion 11^a of tracks 11 which incline downwardly and terminate adjacent to the sprocket wheels 9, the rear portions of said tracks being curved upwardly at 11^b, outside of the sprocket wheels, whereby the receptacles or pallets that are delivered from the horizontal portions of tracks 7 will descend between the curved portions 7^a, 11^a and travel down the inclined tracks 11 to be elevated by the sprocket wheels 9 for delivery to the tracks 7. The parts above described are substantially similar to my Letters Patent No. 1,027,084 granted May 21, 1912, and to corresponding parts shown in U. S. Letters Patent No. 1,027,110 granted May 21, 1912. Ore or other material to be treated may be delivered into the movable receptacles or pallets from a hopper 12, and flame for ignition of the material in the receptacles may be supplied from a gas pipe and burners, at 13, in a well known way. In the aforesaid Letters Patent, the lower surfaces of the receptacles near their edges slide upon wearing strips and the rollers or wheels of the receptacles are not intended to roll upon tracks or rails, which merely serve as guides for the receptacles. In accordance with my invention the wheels or rollers 5 of the receptacles or pallets always travel upon the tracks 7. At 14 is one or more suction or wind boxes provided with opening 15 to which a pipe connected with an air exhaust apparatus or blower, such as a centrifugal fan, may be connected and operated in any usual way for producing exhaust in the wind box to cause air to blow through the material upon the grate bars of the pallet. The suction or wind box or boxes are supported upon the main frame in any usual way. The tracks 7 may be cast integral with the wind box, as shown in Fig. 3, or may be sepa-

rate and attached thereto, as illustrated in Figs. 4 and 5, where the webs 7^b of the tracks 7 are riveted to the adjacent walls of the wind box.

In my present improvements the surfaces of the receptacles or pallets adjacent to the wind box do not slide upon rigid rails for their support nor to make air tight joints, but are spaced from the wind box so that as the wheels 5 of the receptacles always travel upon the tracks 7 the receptacles will not encounter the metal of the wind box or of the tracks. To seal the spaces between the receptacles or pallets and the wind boxes I provide relatively soft and flexible strips of material, indicated at 16, which may be secured to the wind box or to the adjacent track to cooperate with corresponding surfaces of the receptacles or pallets, or may be secured to the latter to cooperate with corresponding surfaces upon the tracks or wind box. The material 16 may be of any suitable construction to resist the flow of air and at the same time bear flexibly against an adjacent sealing surface, such as hemp or asbestos cloth preferably impregnated with lubricating substance, such as with graphite or similar materials, whereby the strips may be made self-lubricating, cheap and easy to replace when worn, and which will not wear the metal of the receptacles or the wind boxes. As shown in Fig. 3 the strips 16 may be detachably secured at the projecting edge portion 14^a of the wind box or the track 7, by means of screws or bolts 17, in position to bear against the surfaces 2^a of the receptacles or pallets, which surfaces are to be preferably machined perfectly smooth. In Fig. 3 the surfaces 2^a are at the sides of the framing of the receptacles 2, whereas in Fig. 4 the surfaces 2^a are upon ribs 2^b projecting laterally from the receptacles to receive the strips 16 to which strips are shown secured by bolts or screws 17 to the rails. Other suitable means may be provided for securing the strips 16 in place in such a manner as to be easily detached and replaced for renewal.

In the form shown in Fig. 5 the strips 16 are secured to rib 2^b of the receptacle or pallet and travel with the latter, bearing against a smooth surface 7^c extending from the rail 7 at the top of the wind box, forming a tight slidable seat between such surfaces.

In the form shown in Figs. 3 and 4 the strips 16 may be of any desired length, whereas in the form shown in Figs. 5 and 6 the strips 16 are applied to each receptacle or pallet and are shown of sufficient length to overlap at the end-to-end portions of adjacent receptacles. In such case one of the strips 16 projects beyond its corresponding receptacle at 16^a and overlaps against the adjacent end of the strip 16 on the next

adjacent receptacle to make tight joints between the overlapping strips.

At opposite ends of the wind box or boxes, where the receptacles or pallets 2 advance to and pass from the latter, dead plates 18 are secured, over which the receptacles slide. In Fig. 7 the strip 16 extends along the dead plate to engage the movable receptacle or pallet. In Fig. 8 strip 16 is carried by the receptacle or pallet to slide along the dead plate. The strips 16 resist leakage of air at the dead plates and the receptacles.

When the machine is operated and a vacuum or suction is maintained in the wind box or boxes 14 such vacuum or suction will tend to pull the flexible sealing strips 16 against the surfaces 2^a or 7^c, so as to prevent air from passing into the wind box at the joints between the moving receptacles or pallets and the wind box, while at the same time the receptacles will be free to travel forwardly either sliding against the flexible strips, or the strips sliding against the surfaces 7^c, with a minimum of wear, friction and consumption of power.

By means of my improvements I am enabled greatly to reduce or obviate the loss of air into or from the wind boxes, and to enable the pallets to travel freely over the wind boxes, thus reducing friction and cost of operation compared with machines of the class described now in use and known to me for sintering, desulphurizing and otherwise treating ores. Such advantages are attained by reason of the fact that the receptacles or pallets do not slide upon metal surfaces but are always supported by their rolls or wheels 5 upon the tracks and that the joints between the receptacles and the wind boxes are relatively soft and flexible with smooth easy sliding contact along the flexible strips and moving parts, so that leakage of air at such strips into or from the wind boxes is obviated and wear upon the moving parts is reduced, while at the same time replacement of the strips, when necessary, may be readily effected at comparatively low cost.

While I have illustrated my invention as embodied in a well known construction of sintering machine it will be understood that my invention is not limited to the details of construction and arrangement of parts set forth, since the same may be varied, within the scope of the appended claims, without departing from the spirit of my invention.

Having now described my invention what I claim is:

1. An ore treating machine comprising a wind box, movable receptacles, means to support said receptacles to travel relatively to the wind box, and flexible material of such flexibility as to effect sealing engagement cooperative between the wind box and receptacles to resist the flow of air between the

wind box and the receptacles at said material.

2. An ore treating machine comprising a frame provided with tracks for movable receptacles, a wind box, movable receptacles, and flexible sealing material providing joints between the wind box and the receptacles to resist the flow of air at such joints.

3. An ore treating machine comprising tracks, a wind box, movable receptacles having wheels to travel upon said tracks, said receptacles being supported by said tracks and wheels wholly out of contact with the wind box, and flexible sealing material cooperative with the receptacles and wind box to resist the flow of air at the joints.

4. An ore treating machine comprising spaced tracks, a wind box, movable receptacles, means to movably support said receptacles upon said tracks wholly out of contact with the wind box, certain of said parts having smooth surfaces, and flexible sealing strips secured to other of said parts and of such flexibility as to effect sealing engagement with said surfaces to provide substantially air tight joints.

5. An ore treating machine comprising a wind box, a plurality of movable receptacles having smooth surfaces, means to support said receptacles to travel relatively to the wind box, and flexible sealing strips supported adjacent to the open side of the wind box to bear against said smooth surfaces of the receptacles to resist the flow of air at said surfaces.

6. An ore treating machine comprising a wind box, movable receptacles, means to support said receptacles to travel relatively to the wind box, and flexible sealing material comprising lubricating material cooperative between the wind box and receptacles and of such flexibility as to resist the flow of air therebetween.

7. An ore treating machine comprising a wind box, movable receptacles, means to support said receptacles to travel relatively to the wind box, and flexible sealing material impregnated with lubricating material cooperative between the wind box and receptacles and of such flexibility as to resist the flow of air therebetween.

8. An ore treating machine comprising a wind box, movable receptacles, means to support said receptacles to travel relatively to the wind box, and flexible sealing material having a lubricous surface and of such flexibility as to effect sealing engagement between the wind box and the receptacles to resist the flow of air into the wind box adjacent to the receptacles.

9. An ore treating machine comprising a wind box, movable receptacles, means to support said receptacles to travel relatively to the wind box, and sealing means comprising flexible air-resisting fabric provided with

lubricating material cooperative between the wind box and the receptacles to resist the flow of air therebetween.

10. An ore treating machine comprising a wind box, movable receptacles, means to support said receptacles to travel relatively to the wind box, and flexible sealing material comprising fabric impregnated with graphite cooperative between the wind box and the receptacles to resist the flow of air therebetween.

11. An ore treating machine comprising a wind box, movable receptacles, means to support said receptacles out of contact with the wind box to travel relatively thereto, and flexible sealing material having a lubricous

surface and of such flexibility as to effect sealing engagement between the wind box and the receptacles to resist the flow of air therebetween.

12. An ore treating machine comprising a wind box, movable receptacles, means to support said receptacles out of contact with the wind box to travel relatively thereto, and flexible sealing material comprising fabric having graphite thereon cooperative between the wind box and the receptacles to resist the flow of air therebetween.

Signed at 41 Park Row, New York, in the county of New York and State of New York, on this 26th day of October, A. D. 1922.

HENRY J. STEHLI.
